UNITED STATES PATENT OFFICE

LEWIS H. BOWN, OF EAST AURORA, NEW YORK, ASSIGNOR TO BUFFALO POTTERY, OF
BUFFALO, NEW YORK

DESIGN FOR A PLATE OR SIMILAR ARTICLE

Application filed July 14, 1932. Serial No. 44,324. Term of patent 3½ years.

To all whom it may concern:

Be it known that I, LEWIS H. BOWN, a citizen of the United States, residing at East Aurora, in the county of Erie and State of New York, have invented a new, original, and ornamental Design for Plate or Similar Article, of which the following is a specification, reference being had to the accompanying drawing, forming a part thereof.

In the accompanying drawing:

Fig. 1 is a plan view of a sector-shaped

portion of a plate or similar article showing my new design.

Fig. 2 is a plan view of the plate or similar article on a reduced scale, and having a portion of the design shown thereon and the remainder of the design indicated in broken lines.

I claim:

The ornamental design for a plate or similar article as shown and described.

LEWIS H. BOWN.
